JOHN WARBURTON, OF PATERSON, NEW JERSEY, ASSIGNEE OF ONE-HALF TO DANIEL WARD, OF PATERSON, NEW JERSEY.

LET-OFF MECHANISM FOR LOOMS.

1,245,290.

Specification of Letters Patent.

Patented Nov. 6, 1917.

Application filed February 16, 1917. Serial No. 148,967.

To all whom it may concern:

Be it known that I, JOHN WARBURTON, a citizen of the United States, residing at Paterson, in the county of Passaic and State 5 of New Jersey, have invented certain new and useful Improvements in Let-Off Mechanisms for Looms, of which the following is a specification.

This invention relates to means for controlling the advance under tension of the cloth and warp in a loom, and it has reference particularly to the so-called let-off part of such means. I seek by this invention principally to obtain an equable tension on 10 the warp under all conditions. For attaining this object the commonly employed expedient involves ropes or chains wound on the let-off warp-supply beam and held tight by weights, which are varied to suit the character 15 of the goods being woven and other conditions. But, especially where the weights require to be heavy, such means develops failure to produce the desired condition of absolute constancy of tension; for 20 instance, if ropes are employed, they will exert different degrees of resistance to rotation of the beam according as they absorb more or less humidity from the atmosphere; in any case, such means is unreliable, the action 25 of the beam being alternate dwells and slips, which lead to "shiers" (i. e., undue spacing of the weft and other imperfections in the cloth.

My invention contemplates a novel combination of parts whereby, given means to take up the warp at a definite rate of advance, the warp is let off at a rate different from that at which it is taken up and is at the same time held taut, the part of the combination which causes the warp to be held taut governing the part which effects the letting off so that from time to time the difference between the rate of letting off and the rate of taking up is compensated for; in the construction herein shown and described by way of illustration, the warp is let off faster than it is taken up, and the compensation involves stopping the let-off action from time to time while the take-up continues.

In the accompanying drawings, in which the invention is fully illustrated,

Figure 1 is a side elevation of a loom embodying my invention;

Fig. 2 is a rear elevation of the improved mechanism;

Fig. 3 is a side elevation, partly in section;

Fig. 4 is a plan view;

Fig. 5 is a plan view like Fig. 4 excepting that the parts are in the position that they 60 occupy when the warp is let back;

Fig. 6 is an inside elevation of a fragment of pawl *w* and its actuating lever; and,

Fig. 7 is a sectional view on the line 7-7 of Fig. 5.

65

In the loom frame *a* there are a take-up means *b*, a batten structure *c* equipped with a reed *d* and a shuttle or shuttles and picking mechanism therefor (not shown); and means *e* to drive the take-up mechanism at a 70 definite take-up rate.

Two stands *f* form a rearwardly projecting part of the frame *a*. They afford a bearing for a shaft *g* having keyed thereto two upwardly projecting arms *h*, in which is 75 journaled the warp-supply or let-off beam *i*, and a rearwardly projecting arm *j*; parts *g*, *h* and *j* form in effect a bell-crank lever.

Journaled in frame *a* are two bell-crank 80 levers *k* equipped with weights *l* and connected with the trunnions of the beam by links *m*, so that levers *g-h-j* and the levers *k* move together on their respective fulcrula.

85 There is a ratchet wheel *o* journaled on shaft *g*, and a system of gearing *p*, *q* *r* and *s* connecting the ratchet wheel with the beam, the member *p* of such gearing being fast with the ratchet wheel, the members 90 *q-r* thereof fixed to rotate together on a suitable bearing of one of the arms *h*, and the member *s* fixed to the end of the beam.

95 Supported by a rigid bracket *t* extending inwardly from one of the stands *f* is a bar *u* which affords a fulcrum for two pawls *v* *w*, the former of which may be gravity-held and the latter spring-held against the toothed periphery of the ratchet wheel. For actuating pawl *v* there is fulcrumed in bar 100 *u* a lever *x* having a hook *x'* overhanging the idle end of the pawl and adapted to retract it when the lever swings to the left. For actuating pawl *w* there is fulcrumed in bar *u* another lever *y* adapted to strike a lug 105 *w'* on pawl *w* when the lever swings to the right and retract the pawl. The levers are connected by a link *z* so as to swing together on their fulcrula, and they are made a going part of the loom by being connected 110

with a crank c' on the batten structure c by a pitman 2. There is thus produced an escapement means which, with the levers w and y kept oscillating and assuming there is a rotating influence being exerted on the ratchet wheel, results in the ratchet wheel and hence the beam rotating step by step in the direction to deliver the warp; the parts are timed so that the rate of delivery of the warp is different from that of its taking up by the take-up mechanism, in the present case at a faster rate. The fulcrum of the lever y is a stud 3 (as shown, also the pivot for pawl w), and the lever is shiftable thereon by virtue of a slot y' which receives it and allows the lever to descend to a position where instead of continuing to strike the pawl a recess y^2 formed therein will oppose the lug w' on the pawl and the pawl will remain unretracted. Lever y is carried by a stirrup piece 4 which is pivotally pendent from arm j and has its lower end turned off and penetrated by a rod 5 and interposed between two springs 6 coiled around the rod between two lugs 7 on the lever, which support the rod (Figs. 6 and 7).

Assume the position of the parts to be as shown in Fig. 3, and the loom to be stopped: The freely shiftable means g , r and i , under the pressure of the train of parts l , k , m , h , g and j is exerting a tautening influence on warp A, the beam i being held against rotation to unwind the warp because geared with the ratchet wheel, which is locked by one of the pawls. If the loom be now started, the pawls will free the ratchet wheel step by step at a faster rate than the warp is taken up, in consequence of which the means l , k , m , h , g and j will force the beam back, which will depress the lever y until finally its recess y^2 opposes the lug w' , so that the lever will cease to withdraw the pawl w ; this hiatus in the retracting movements of the pawl may endure for one or more oscillations of the levers, but since pawl w remains holding the ratchet wheel and only pawl v continues in motion, it will terminate as soon as the take up means has returned the beam forward and consequently elevated the lever y to the position where it will again actuate pawl w , whereupon the warp will again be delivered at a rate in excess of its taking up, and so on. It will be observed that always the tension remains absolutely equable.

If it should be necessary to advance the warp for any purpose to bring the fell of the cloth forward of its normal position (indicated by arrow B in Fig. 1), or if due to a "smash" it be forced forward, or if it is necessary to let back the warp, the abnormal movement of stirrup 4 incident thereto is taken up by one or the other of the springs 6. Assume the warp to be advanced, for instance, so as to leave a cut-off mark in the

cloth by absence of filling, the parts g , h , j would be tilted forward, which would compress upper spring 6; the mechanism, on being now set in motion, would deliver the warp at a rate exceeding its taking up until said spring became restored to normal condition and the lever y thereupon falls sufficiently to clear the pawl w and cease to actuate it. Conversely, assume the warp to be let back (Fig. 5), lower spring 6 would be compressed; on setting the mechanism in motion, since pawl w is now idle due to lug w' of pawl w being opposed to it, the beam remains held against rotation until the take-up, through the warp, has drawn it forward and consequently elevated lever y to such position that in vibrating it will again put pawl w in motion.

I do not wish to be limited to the details of construction herein set forth, what I claim being:

1. In combination, with a take-up mechanism, a let-off mechanism including a freely shiftable warp-tautening rotary warp-supply beam and means, controlled by the shifting beam, for controlling the letting-off rotation of the beam, said means including a rotary element connected to rotate with the beam and a going step-by-step means controlling the rotation of said element. 95

2. In combination, with a take-up mechanism, a let-off mechanism including a freely shiftable warp-tautening rotary warp-supply beam and means, controlled by the shifting beam, for controlling the letting-off rotation of the beam, said means including a rotary element connected to rotate with the beam, a pair of check devices movable into and out of and normally held in checking relation to said element, and separate going instrumentalities to impart retracting movement to each of said devices. 100

3. In combination, with a take-up mechanism, a let-off mechanism including a shiftable fulcrumed warp-tautening structure 110 having a warp-rotated beam, and means, controlled by the shifting fulcrumed structure, for controlling the rotation of said beam including a rotary element connected to rotate with the beam and a going step-by-step means controlling the rotation of said element. 115

4. In combination, with a take-up mechanism, a let-off mechanism including a shiftable fulcrumed warp-tautening structure 120 having a warp-rotated warp-supply beam, and means, controlled by the shifting fulcrumed structure, for controlling the rotation of said beam including a rotary element connected to rotate with the beam and a going step-by-step means controlling the rotation of said element. 125

5. In combination, with a take-up mechanism, a let-off mechanism including a shiftable fulcrumed warp-tautening structure 130

having a warp-rotated beam, and means, controlled by the shifting fulcrumed structure, for controlling the rotation of said beam including a rotary element journaled 5 concentric with the fulcrum of said structure and connected to rotate with the beam and a going step-by-step means controlling the rotation of said element.

6. In combination, with a take-up mechanism, a let-off mechanism including a shiftable, fulcrumed warp-tautening structure having a warp-rotated warp-supply beam, and means, controlled by the shifting fulcrumed structure, for controlling the rotation 10 of said beam including a rotary element journaled concentric with the fulcrum of said structure and connected to rotate with the beam and a going step-by-step means controlling the rotation of said element.

7. In combination, with the frame, a take-up mechanism arranged therein and a let-

off mechanism including a shiftable up-standing warp-tautening structure having a warp-rotated beam and fulcrumed in the 25 frame with its axis parallel to the beam, means normally acting to move said structure relatively away from the take-up mechanism, and means, controlled by the shifting warp-tautening structure, to control 30 the rotation of the beam.

8. In combination, with the frame, a take-up mechanism arranged therein and a let-off mechanism including a shiftable up-standing warp tautening structure having a 35 warp-rotated beam and fulcrumed in the frame with its axis parallel to the beam, a rotary element journaled in the frame concentric with said axis and connected to rotate with the beam, and means, controlled 40 by the shifting warp-tautening structure, to control the rotation of said element.

In testimony whereof I affix my signature.
JOHN WARBURTON.
